US00D852736S

(12) **United States Design Patent** (10) Patent No.: **US D852,736 S**
Goodman et al. (45) Date of Patent: ** Jul. 2, 2019

(54) **SUPPORT MEMBER ENDS FOR SOLAR PANEL TRUSS MOUNTING SYSTEMS**

(71) Applicant: **Georgia Tech Research Corporation**, Atlanta, GA (US)

(72) Inventors: **Joseph Neal Goodman**, Snowmass, CO (US); **Tristan Farris Al-Haddad**, Clarkson, GA (US)

(73) Assignee: **Georgia Tech Research Corporation**, Atlanta, GA (US)

(**) Term: **15 Years**

(21) Appl. No.: **29/615,474**

(22) Filed: **Aug. 29, 2017**

Related U.S. Application Data

(60) Continuation of application No. 15/069,326, filed on Mar. 14, 2016, now Pat. No. 9,882,524, which is a division of application No. 14/849,835, filed on Sep. 10, 2015, now Pat. No. 9,379,660, which is a division of application No. 14/043,793, filed on Oct. 1, 2013, now Pat. No. 9,163,861.

(57) **CLAIM**

The ornamental design for the supported member ends for solar panel truss mounting systems, as shown and described.

DESCRIPTION

FIG. 1 is a perspective view of a support member ends for solar panel truss mounting systems, showing our new design;

FIG. 2 is a front elevation view thereof;

FIG. 3 is a back elevation view thereof;

FIG. 4 is a right-side elevation view thereof; and,

FIG. 5 is a left-side view elevation view thereof.

1 Claim, 5 Drawing Sheets
